FIG. 1.

FIG. 2.

FIG. 3.

FIG. 4.

FIG. 5.

FIG. 6.

FIG. 7

FIG. 8.

FIG. 9.

FIG. 10.

FIG. 11.

FIG. 12.

FIG. 1 is a perspective view taken from the front, top and one side of a valve operator casing showing my new design;

FIG. 2 is a rear elevational view thereof;

FIG. 3 is an elevational view taken from the side opposite that shown in FIG. 1;

FIG. 4 is a bottom plan view thereof;

FIG. 5 is a perspective view taken from the front, top and one side of a modified form of the valve operator casing shown in FIG. 1;

FIG. 6 is a rear elevational view of FIG. 5;

FIG. 7 is an elevational view taken from the side opposite that shown in FIG. 5;

FIG. 8 is a bottom plan view of FIG. 5;

FIG. 9 is a perspective view taken from the front, top and one side of a second modified form of the valve operator casing shown in FIG. 1;

FIG. 10 is a rear elevational view of FIG. 9;

FIG. 11 is an elevational view taken from the side opposite that shown in FIG. 9; and

FIG. 12 is a bottom plan view of FIG. 9.

The broken line representation of various operating components of the fully assembled valve operator on FIG. 1 is for purposes of illustration only.

I claim:

The ornamental design for a valve operator casing, substantially as shown and described.
